UNITED STATES PATENT OFFICE.

JOHN LOFTUS, OF ALBANY, NEW YORK.

ELASTIC SEAT.

No. 829,978.

Specification of Letters Patent.

Patented Sept. 4, 1906.

Application filed January 29, 1906. Serial No. 298,499.

To all whom it may concern:

Be it known that I, JOHN LOFTUS, a citizen of the United States, residing at Albany, in the county of Albany and State of New York, have invented certain new and useful Improvements in Elastic Seats; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to new and useful improvements in elastic supports especially adapted for use in connection with chairs, locomotive-seats, &c.; and the object of the invention is to produce a support having a circular compression coil-spring having radial connection with a seat for attachment thereto and by which a small spiral spring will sustain a comparatively great weight.

20 The invention consists, further, in various details of construction and combinations and arrangements of parts, which will be herein-after fully described and then specifically defined in the appended claim.

25 My invention is illustrated in the accompanying drawings, in which—

Figure 1 is a sectional view through a seat, showing the application of my invention. Fig. 2 is a bottom plan view. Fig. 3 is a detail view of the coil-spring, and Fig. 4 is a detail view of a slight modification of the invention.

30 Reference now being had to the details of the drawings by letter, A designates the top of a casing, and B the bottom, each of which has a central opening A', and intermediate the covers is a spiral spring B', mounted in any suitable manner, and D is a flange which is secured to the marginal outline of the aper-

ture A' and extends within the casing and affords means for holding the coil-spring to its seat in place and also serving as a guide to the circular-outlined block E, which has a shank portion E'.

35 G G designate spiral chains or wires or other suitable connection intermediate the ring F and coil-spring, and in Fig. 4 of the drawings I have shown a slight modification of details of my invention in which I have illustrated a wire G^X, the strands of which intersect one another, as at F^X, and engage over portions of the coil B' at location diametrically opposite.

40 From the foregoing it will be observed that by the peculiar construction of my invention a suitable elastic seat is provided in which the strain is distributed equally in radial directions.

45 While I have shown a particular application of my invention illustrating a circular-outlined block which yields, it will be understood that nearly the entire surface of the top may be mounted to have the yielding action and various shapes of tops may be utilized without in any way departing from the spirit of the invention.

50 What I claim is—

55 An elastic seat comprising a casing, a coil-spring mounted therein, a yielding member mounted in an opening in said casing, a ring secured to said member, radial connections between said ring and spring, and a flange about the periphery of an opening in said casing and extending within the casing, as set forth.

60 In testimony whereof I hereunto affix my signature in the presence of two witnesses.

JOHN LOFTUS.
